UNITED STATES PATENT OFFICE.

HERMANN WERNER, OF STUTTGART, GERMANY.

OVEN.

SPECIFICATION forming part of Letters Patent No. 628,052, dated July 4, 1899.

Application filed May 28, 1897. Serial No. 638,593. (No model.)

To all whom it may concern:

Be it known that I, HERMANN WERNER, a subject of the King of Würtemberg, residing at Panoramastrasse 11, Stuttgart, Germany, 5 have invented new and useful Improvements in Ovens, of which the following is a specification.

This invention relates to bake-ovens; and it consists, substantially, in such features of 10 improvement as will hereinafter be more particularly described.

Most bake-ovens with pipe-heaters have the disadvantage that in consequence of the arrangement of the furnace at the back part 15 and the charging-opening of the hearth at the front part the baking, which is first put in, in addition to remaining a perceptibly longer time in the oven than that last put in is also exposed to a greater heat. For this reason a 20 uniform baking of all the ware cannot be obtained, and this action is especially injurious to small wares. A further disadvantage of the above-described heating arrangement is that the closed tubes, partly filled with water 25 and serving for heating, must have an incline upward, and, if the furnace is at the back, as hitherto customary, rise from the back toward the front, having also an incline opposite to that of the hearth, which, as is well known, 30 rises toward the rear from the charging-opening. The consequence of this is that the upper heating-tubes are very near the baking-hearth at the back part of the oven, while at the forward part, on the contrary, they stand off quite a distance from it, and since, furthermore, the front wall is, so to speak, a "cooling-wall," while the rear wall, on the contrary, is 35 a strongly-heated heating-wall, the heat in the rear part of the baking-chamber is considerably higher in comparison with that in 40 the forward part of the baking-chamber. My new arrangement completely obviates these disadvantages, since the furnace is arranged forward of the bake-oven, lying sidewise to 45 the same, whereby the fire-charging opening can be located laterally or facing forward at the front part of the oven. Furthermore, the heating-pipes are bent to an angle form and, rising up from the furnace, lead first cross- 50 wise of the oven, about half the pipes lying above the others, and then from the bend are distributed in the baking-chamber regularly,

substantially parallel with the sloping hearth, in the direction of the length of the oven.

Figure 1 is a vertical transverse sectional view of a bake-oven having my improvements embodied in connection therewith, the fire-chamber in this instance being shown as opening or accessible from the side of the oven. Fig. 2 is a vertical longitudinal sectional elevation of the fire-chamber, having its charging-opening at the side. Fig. 3 is a sectional plan view of an oven having two fire-chambers at the side, the charging-openings for said chambers being located at the front and back 65 of the oven. Fig. 4 is a sectional plan view of an oven, showing the door of the fire-chamber located at the front thereof, part of the baking-chamber and a part of the heating-pipes being broken off at one end. Fig. 5 is 70 a vertical transverse sectional elevation taken through the baking-chamber on a different line from that in Fig. 1. Fig. 6 is a complete sectional plan view similar to Fig. 4, but showing the door to the fire-chamber as located to 75 one side of the oven, at the front part of the baking-chamber.

My improved bake-oven A is constructed with a baking-chamber A' and also with a fire-chamber A², the latter being provided with a 80 fuel-grate B and a fuel-charging opening B², closed by a door b. Said fire-chamber A² is located to one side of the oven, at the front part of the baking-chamber A', and the door b of the charging-opening B² may be arranged 85 directly at the front of the oven or it may be at the side, as shown in the several figures of the drawings. The fire-chamber A² extends upward almost the full height of the oven, and the same is separated from the baking- 90 chamber by means of a division-wall M.

The bottom 1 of the baking-chamber slopes or inclines upwardly from the division-wall M to the opposite inner wall 2, (see Figs. 1 and 5,) and the under side of the top portion 95 3 of said baking-chamber also slopes or inclines in the same direction correspondingly. The said chamber is divided into two or more compartments 5 and 6 by means of a horizontal partition-wall 7, also inclined or sloping 100 in the same direction, the said wall on its top or upper surface constituting a hearth for the upper compartment 5 and the bottom 1 of the baking-chamber constituting a hearth for the

lowermost compartment 6. The said compartments 5 and 6 are each accessible through a charging-opening 8 at the front of the oven, and said openings are closed by doors c. It 5 is through these openings that the articles to be baked are introduced. Preferably, though not essentially, I sometimes construct each of the said hearths with a drip-pan D, forming, practically, a part of the hearth and serving 10 to catch any moisture that may arise or form in the compartments, and leading from each of said pans to the front of the oven or baking-chamber is a pipe or conduit 9 for conveying away such moisture.

15 Located or arranged in each of the compartments 5 6 of the baking-chamber A' is a shelf C, which for a distance about equaling the length of the fire-chamber A² is truly horizontal, as seen in Fig. 1; but for the remaining 20 depth or extent of said compartments the said shelves are inclined substantially in conformity or correspondence with the inclinations of the floors or hearths of the compartments and toward the front of the oven. In 25 this way the baking-pan, which may be placed on the horizontal portions of said shelves, will serve as a means of holding other pans in place, which may be introduced or arranged on the inclined or sloping portions of the 30 shelves.

The heating-pipes for the baking-chamber are shown in four double series at E E', and, as indicated in Figs. 1, 2, 3, 4, and 6, one end of the pipes of each double series passes 35 through suitable openings therefor in the division-wall M and enters the fire-chamber A², and in this way the pipes are heated by the products of combustion arising in said chamber. As shown in Fig. 1, the ends of the said 40 double series of pipes in their vertical arrangement or disposition enter each the said fire-chamber successively to a greater extent, so that the said pipes are equally exposed to the heat in the fire-chamber. The series E of 45 each double series of pipes extend straight through the wall M, and they are then bent substantially at right angles and upwardly substantially in correspondence with the incline or slope of the hearths or floors of the 50 compartments 5 6 of the baking-chamber. (See Fig. 5.) The number of pipes E in the series is sufficient to make up a horizontal row practically equal to the length of the fire-chamber, and each pipe, as is shown, extends 55 a little farther into the baking-chamber, so that all the pipes of this series E together cover an area equal to about one-half the

length of the shelves C. The series of pipes E' are arranged beneath the series E at the fire-chamber and also extend beneath the 60 same until the point of the bend therein is reached, (see Fig. 6,) after which the said pipes E' are spread out horizontally to practically fill or cover the remaining area of the compartments 5 6. From the point of the 65 bends in the two series the pipes are converged or gradually brought together until at the ends they unite and are supported by means of ledges m, projecting from the inner wall 2 of the oven. By arranging the pipes 70 of each double series one above the other at the fire-chamber I am enabled to obtain an equal distribution of heat without increasing the length of said fire-chamber.

It will be seen that a double series of pipes 75 is arranged both above and below the shelf C of the compartments 5 6 of the baking-chamber, and thus there is an equal distribution of heat on both sides of each of said shelves. By converging or bringing together the ends 80 of the pipes of each double series the heat is also in a measure concentrated at the rear part of the baking-chamber, with the result of uniformity in the baking of bread and other articles.

85 It is evident that immaterial changes or alterations can be made in the general construction and arrangement of parts of my improved oven without departing from the spirit of my invention.

90 I claim—

An oven constructed with a baking-chamber divided into compartments by a horizontal inclined partition-wall, each compartment having an opening closed by a door, a fire-chamber at the front of the oven to one side of said baking-chamber, a horizontal inclined shelf in each compartment, double series of heating-pipes leading from the fire-chamber intermediate the hearth and shelf of each compartment, and similar series of pipes arranged above and below the partition-wall, the pipes of each double series being bent upwardly at substantially right angles, and converging at their inner ends and supported from interior 100 ledges of the oven, substantially as shown and described.

105 In testimony whereof I have signed this specification in the presence of two subscribing witnesses.

HERMANN WERNER.
